HOISTING DEVICE

Samuel Winkel, Miami Beach, Fla.

Application July 2, 1947, Serial No. 758,604

3 Claims. (Cl. 212—61)

1

The present invention relates to a portable hoisting device and it particularly relates to a light weight hoisting device which may be conveniently utilized in hoisting construction materials during construction or repair of buildings and readily moved from floor to floor.

It is among the objects of the present invention to provide a simple, inexpensive durable material hoisting device which may be readily placed upon building constructions and which may be utilized to hoist materials at least up to four stories in height.

Another object is to provide a simple inexpensive hoisting device which may be readily installed and operated by one or two men without the necessity of building expensive elevators and without requiring services of carpenters to build elevator shafts.

Another object is to provide a simple inexpensive electrically operated material hoist which may be set up in a short period of two hours and which may be conveniently used for hoisting construction materials including concrete or cement blocks, steel framework, brick mortar, window frames, radiators, and so forth up to the upper floors.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

The above objects are most satisfactorily accomplished by providing a rotatable boom structure mounted on a central post. The boom carries and is balanced by a motor, clutch and brake structure designed to be positioned over and extend beyond the central bearing post. The boom is pivotally mounted on the top of the central post by a cap and by a detachable collar attached to the lower part of the boom structure.

Desirably brake and clutch structures are mounted on one shaft manually actuated by separate angularly spaced levers and are positioned in readily accessible position at one side of the machine. The first shaft drives a parallel winch drum shaft. The motor shaft is at right angles to the first shaft and is connected to drive said shaft by bevel reduction gears.

The invention also consists in certain new and original features of construction and combination of parts hereinafter set forth and claimed

2

as to its other objects, features and advantages, the mode of operation and manner of its organization, these, *inter alia*, may be better understood by referring to the following description considered in connection with the accompanying drawings forming a part thereof in which:

Fig. 1 is a side perspective view of the hoisting device according to one embodiment of the present invention;

10 Fig. 2 is a side elevational view showing the detail construction, and

Fig. 3 is a top plan view.

Referring to Fig. 1 there is a base structure A, a rotatable boom structure B and an electric 15 motor drive construction C and a winch construction D.

The base structure A has a base plate 10 with inclined sides 11 and a back 12 carrying the angle member 13. The post or vertical pivotal mount member 14 is supported by the inclined base members 15 which are welded at 16 to the post 14. The boom rides on the post 14 by the lower bearing sleeve 17 and the upper cap member 18.

25 The lower bearing member 17 has an outwardly extending flange 19 which is bolted at 20 to the flange 21 extending horizontally toward the post 14 from the lower ends 22 of the lower structure members or angle beams 23 of the boom structure B. By removing the bolts 20 30 it is possible to separate the flanges 19 and 21 and thus detach the bearing 17 from the boom structure B which may then be lifted from the top of the post 14.

35 The cap member 18 carries the lower end 24 of the upper boom structural members 25 which also consist of forwardly and upwardly angle members. The angle members 23 and 25 are joined together at their upper ends by welding or by bolts or rivets 26. The top plate 27 may 40 be welded to the upper flanges 28 of said angle beams 25.

Between the angle members 23 and 25 there 45 extends the vertical brace members 29, the horizontal brace members 30 and the vertical brace members 31. The ends of these brace members 29, 30 and 31 are welded or bolted to the top and bottom flanges 28 and 32 of the angle beams 23 and 25 or to the side flanges 33 and 34 thereof. It will be noted that the lower angle members 33 are bent at 71 so that the edges of the vertical flanges 33 and 34 will contact at 35 and 50 may then be welded together to give a most rigid structure.

55 On the lower ends of the horizontal flanges

28 of the beams 25 is positioned the base member 36. The member 36 carries the upwardly extending frame structure 37 (see Fig. 2) having the flanges 38 and 39 bolted at 40 and 41 to the spacer blocks 42 and 43 and the flanges 28.

The U-member 37 carries the bearing members 44 and 45 which carry the shafts 46 and 47 (see Fig. 2). These bearing members 44 and 45 are provided with the flanges 48 and 49 bolted down at 50 and 51 (see Fig. 3). The other ends of the shafts are carried by the bearings 52 and 53 having the flanges 54 which are bolted down at 56 and 57.

The shaft 46 carries the cable drum 58 (see Figs. 2 and 3) carrying the cable 59 which leads to the pulley 60. The end of the cable 59 is connected to the wheel 61 by the loop 62 formed by the clip 63. The wheel 61 has a cross member 64 mounted on the pin 65. The pin 65 carries a loop 66. The loop 66 passes through the eye 67 of the hook 68 to which may be attached the handle 69 of the bucket 70. The hook also may be used for carrying grapples or for other purposes, such as moving cement or concrete blocks, steel framework and so forth.

The drum 58 is driven by a large gear 90 on the shaft 46 which meshes with the small pinion 91 on the shaft 47. The pinion 91 is driven on the shaft 47 by the bevel gear 92. The bevel gear 92 is driven by the small bevel gear 93 which is connected by the shaft 94 extending through the motor bearing 95.

The motor 96 may consist of a small 1½ H. P. motor rotating at 1750 R. P. M. with a reduction of 4 to 1 from the motor shaft 97 to the intermediate shaft 47 and another reduction of 4 to 1 from the shaft 47 to the main drum shaft 46. The motor base 98 has the flanges 99 bolted at 100 to the plate 101. The plate 101 is mounted on the side channels 102.

The channels 102 interiorly receive the plate 103 on their inturned bottom flanges 104. The entire box structure 101, 102 and 103 is mounted by the brackets 105 from the structural element 106. The structural element 106 is mounted on the plate 36.

The forward plate 107 and the rear plate 106 (see Fig. 1) support the brake structure E and the clutch structure F.

As shown in Fig. 1 the brake structure E consists of a drum 108 on the shaft 109 on the same axis as the shaft 47. The drum 108 is encircled by a brake band 110 which is normally held in active position by the spring 111 reacting against the flange 112 of the bracket 113. The handle 114 is connected by the pivotal connection 115 to the shoe 116. The shoe 116 is mounted on the plate 117 of the end 118 of the brake band 110. By pulling the handle 114 in the direction 119 (see Fig. 1), it is possible to compress the spring 111 and stop the drum 108.

In respect to the clutch F, the clutch disks 130 (see Fig. 3) connected to the bevel gear 92 may cause the bevel gears 92 and 93 to disengage. These clutch disks 130 are operated by the grooved element 131 which receives the finger 132 at the end of the extension 134 of the clutch handle 135. The clutch handle 135 is pivotally mounted at 133 on the bracket 106. The handle 135 is provided with the two hand contact members 136 riveted or bolted together at 137.

In operation, the motor C operates continuously and the drum 58 may be operated and stopped by operation of the levers 135 and 114.

controlling the brake and clutch mechanisms respectively.

The motor C and box 101, 102 and 103 will counterbalance the boom B, and the clutch structure F, brake structure E and winch structure 58 will place sufficient weight directly on post 14 to enable the entire boom readily to be rotated. The cap bearing 18 and sleeve bearing 17 may be provided with grease nipples.

10 The boom B may be readily lifted from the post 14 together with motor C, clutch F and brake E by removing bolts 20.

15 During tests made at a height of 30 feet, the machine as shown lifted 350 pounds or the equivalent of a full wheelbarrow of concrete and returned the hook to the ground, ready to receive another load in a total lapsed time of one minute. The machine as shown will lift a 400 pound load a height of 75 feet within one minute.

20 The load limit of the machine is 400 pounds using a 1½ H. P. electric motor. Heavier loads can be lifted by employing a larger motor.

25 As many changes could be made in the above lightweight portable hoisting device and many apparently widely different embodiments of this invention could be made without departing from the scope of the claims, it is intended that all matter contained in the above description or shown in the accompanying drawings shall be interpreted as illustrative and not in a limiting sense.

What is claimed is:

1. A crane comprising a base, a vertical post upon said base, braces extending upwardly from said base at an incline towards said post and having their upper ends secured to the post in downwardly spaced relation to the upper end thereof, a boom extending from said post radially thereof at an upward incline and having transversely spaced upper beams and transversely spaced lower beams, the lower beams extending outwardly in converging relation to the upper beams and having inner ends spaced downwardly from inner ends of the upper beams and their outer ends rigidly secured to outer ends of the upper beams, there being struts between the upper and lower beams, a cap carried by inner end portions of the upper beams and constituting a bearing rotatably fitting about the upper end 35 of said post above said braces and shiftable upwardly off of the post, a collar loosely fitting about said post below the braces and detachably connected with inner ends of the lower beams, a pulley at the outer end of said boom, a supporting structure mounted over rear portions of the upper beams, a drum on said supporting structure, a cable wound about said drum and extending towards the outer ends of the upper beams and downwardly about said pulley and carrying a load engaging member at its free end, a motor support carried by the inner ends of the upper beams and projecting from the post longitudinally of the boom at the opposite side of the post from the boom, a motor mounted on said motor support, and mechanism carried by said supporting structure for transmitting rotary motion from said motor to said drum.

2. A crane comprising a base, a vertical post rising from said base and braced by diagonal braces extending upwardly from the base and having upper ends secured to the upper portion of the post, a boom extending from the post radially thereof at an upward incline and including upper and lower members having rear ends spaced vertically from each other, a cap carried

by the rear ends of the upper member and rotatably fitting about the upper end of said post above said braces and being movable upwardly off of the post, a collar loosely fitting about said post below the braces and constituting a bearing detachably connected with the rear end of the lower member, a supporting structure extending upwardly from the rear portion of the upper member, a drum rotatably carried by said supporting structure forwardly of the post, a cable wound about said drum and extending towards the front end of the boom and downwardly therefrom and having a load carrier at its free end, a motor support extending from the upper member and projecting radially from the post at the 15 opposite side thereof from the boom, a motor mounted upon said motor support and constituting a counterweight for the boom, and mechanism upon said supporting structure back of said drum constituting means for transmitting rotary motion from said motor to said drum.

3. A crane comprising a vertical post, a boom extending from said post at an upward incline and mounted for swinging movement about the post, a supporting structure mounted over the 20 rear end portion of said boom, a drum mounted upon said supporting structure forwardly of the post, a cable wound about said drum and ex-

tending therefrom along said boom to the front end thereof and downwardly and provided with load engaging means at its front end, a motor support extending from the rear end of said boom longitudinally thereof and projecting from the post at the opposite side thereof from the boom, a motor upon said motor support constituting a counterbalance for the boom, mechanism upon the supporting structure for transmitting rotary motion from said motor to said drum, said motor support consisting of a hollow casing open at its rear end whereby weights may be placed within the casing and assist counterbalancing of the boom.
